UNITED STATES PATENT OFFICE

WILLIAM FINNEY HILLPOT, OF FRENCHTOWN, NEW JERSEY

INCUBATOR MECHANISM

Application filed March 24, 1928. Serial No. 264,320.

My invention relates to mechanism of the general character described and claimed in Letters Patent of the United States 1,489,597 granted to me April 8, 1924 and 1,545,425 granted to me July 7, 1925, wherein the means for supporting eggs include a vertical series of trays each supported by detachable connection with a plurality of vertically extending endless chain belts; whereby each tray is pivotally supported so that it may be tilted, to and from horizontal position, and inclined in either of two opposite directions to turn the eggs, with the object and effect of preventing the embryos from sticking to the shells; and each tray may be progressed vertically during the incubating period, from the place of introduction of the fresh eggs to the place of discharge of the hatched chicks. Each of said trays has freedom for such tilting movement, independently of its vertical movement of progression, but is capable of being contemporaneously tilted and progressed. That is to say, the portions of the mechanism respectively operative to effect the movements of tilting and progression may be operated at different times, or contemporaneously.

In the form of my invention shown in said Letters Patent, four such vertically extending endless chains are used to support the trays and means other than said supporting chains are employed to hold the trays in any position in which they may be tilted; such means being required because the trays are pivoted upon axes coincident with their centers of gravity and thus normally in unstable equilibrium. On the contrary, my present invention is operative with but three vertically extending suspension chains and the trays are supported, in stable equilibrium, in every position of inclination, by said chains; without the necessity of employing other holding means.

Moreover, the construction and arrangement of my present invention are such that all of the trays in a vertical series may be

simultaneously tilted merely by relative movement of their supporting chains; which chains may be simultaneously moved to progress all of the trays in that series without changing their inclination, or, as above contemplated, the chains may be shifted to contemporaneously effect tilting and progressing movement of the entire series of trays which they support.

My invention includes the various novel features of construction and arrangement hereinafter more definitely specified.

In said drawings; Fig. I is a fragmentary, diagrammatic, perspective view of a vertical series of egg trays supported by three vertical chains respectively suspended from chain wheels on three rotary shafts.

Fig. II is an end elevation of one of the trays shown in Fig. I, indicating the range of its inclination with respect to its pivotal connection with the chain at the right hand side of Fig. I; such connection being eccentric with respect to the width of the tray.

Fig. III is a fragmentary, diagrammatic, perspective view of a single tray having three points of suspension with respect to three vertical chains; the right hand chain being pivotally connected with the edge of the tray instead of intermediate of its ends, as in Figs. I and II.

Fig. IV is a fragmentary, diagrammatic, perspective view of a single tray, similar to Fig. III, but showing a location of the intermediate chain different from that in Fig. III; said intermediate chain being pivotally connected with the tray intermediate of its length instead of at the end corner as in Fig. III.

Fig. V is an end elevation of a single tray indicating the range of inclination with respect to its pivotal connection with the two suspension chains at one edge thereof, as in either of Figs. III or IV.

Fig. VI is a fragmentary end elevation of a convenient form of gearing cooperatively

90

connecting the two chain shafts shown at the left in Fig. I; the third shaft, shown at the right in Fig. I, being connected with the bottom shaft at the left in Fig. I by the horizontal chain indicated in dash and dot lines in Fig. I.

Fig. VII is a fragmentary longitudinal sectional view of the mechanism shown in Fig. VI, taken on the line VII, VII in Fig. VI.

10 Fig. VIII is a perspective view of the tray pivot at the right hand side of the tray indicated in Fig. VII; the opposite pivot being oppositely counterpart thereto.

15 Fig. IX is a perspective view of the tray pivot indicated at the remote end of the top tray in Fig. I.

Fig. X is a plan view of the backing bar shown diagrammatically in Fig. I.

Referring to Fig. I; the vertical series of 20 similar trays 1 are supported with freedom for tilting and vertical bodily movement by the three vertically extending endless chains 2, 3 and 4 with which each of said trays 1 is adapted to be independently detachably connected by respective pivot means 5, 6, and 7. A preferred form of pivot member 5 is shown in Fig. VIII and includes a downwardly turned hook member 8 which is adapted to extend in a link of the chain 2. The opposite 30 pivot means 6 is similar to that shown in Fig. VIII, but oppositely counterpart and adapted to extend in a link of the chain 3. The pivot means 7 is shown in Fig. IX and includes the downwardly turned hook 9 adapted to extend 35 in a link of the chain 4. The arrangement is such that by relative movement of said chains 2, 3 and 4; each of said trays 1 is adapted to be tilted upon its axis coincident with the hook member 9 of its pivot 7, to and 40 from horizontal position, and inclined in either of two opposite directions, as indicated by the dotted lines in Fig. II.

It may be observed, with reference to Fig. II, that the axis of the pivot means 7 is eccentric with reference to the width of the tray; so that the latter is always overbalanced toward the right to stress the chain 2 downwardly by the weight of the contents of the tray and thus maintain each tray in stable 50 equilibrium upon its three points of support 5, 6, and 7. However, said points of support may be otherwise disposed. For instance, as indicated in Fig. III; the pivot means 7 is pivotally connected with the edge 55 of the tray instead of intermediate of its end, as indicated in Figs. I and II. Fig. IV shows an arrangement of the pivot means 6 and 7 similar to that of Fig. III; but the pivot means 5 for engagement with the intermediate 60 chain 2 is connected with the tray intermediate of its length, instead of at the ends corner as in Fig. III. In any of the three cases aforesaid, each tray is supported 65 in stable equilibrium upon its three pivotal

means, in connection with the three chains 2, 3 and 4.

As indicated in Fig. I; the chains 2, 3 and 4 are respectively suspended from chain wheels 12, 13 and 14 respectively rigidly connected with rotary shafts 15, 16 and 17, and it is to be understood that when said shafts are contemporaneously turned in the direction of the arrows upon said wheels, the entire series of trays 1 may be bodily lowered; to thus progress each tray from the position of insertion of fresh eggs in the incubator, at the upper portions of said chains, to the position of discharge of chicks from the trays at the lower portion of said chains. Also that the tilting movements of said trays above described may be effected by relative vertical movement of said chains. For instance, the chains 2 and 3 may be relatively shifted, for instance, respectively up and down, while the chain 4 remains stationary, with the effect of tilting all of the trays 1, simultaneously, upward at the right hand edge thereof, as indicated in Figs. I and II. Reverse relative movement of said chains 2 and 3, with said chain 4 stationary, effects tilting movement of the trays to incline the same in the opposite direction. Moreover, it is to be understood that the trays may be tilted and inclined contemporaneously with their downward progressive movement by proper movement of the chain 4 in coordination with the other chains, as hereinafter described.

In Figs. VI and VII, I have shown a convenient gearing mechanism for cooperatively connecting said three shafts 15, 16, and 17 to coordinate effect the above contemplated movements thereof. Said mechanism includes the metallic base frame 19 which may be rigidly connected with the vertical support 20 which may be a timber stud in or at a wall of the incubator inclosure in which said trays 1 are suspended. Said frame 19 has journal bearings 22 and 23 for the respective shafts 15 and 16 aforesaid. Said shaft 15 upon which the suspension chain wheel 12 is rigidly mounted, is provided with means for turning it, manually or otherwise, conveniently including the chain wheel 25 which is rigidly connected therewith and may be turned directly by hand or by means of an endless chain encircling it and pendent therefrom, as indicated at 26 in Fig. VII. Said shaft 15 has, rigidly mounted thereon, the sun gear 27 in mesh with the planetary gear 28 which is journaled on the spider 29 in the gear casing 30. Said planetary gear 28 is in mesh with the second sun gear 32 which is in coaxial relation with said first sun gear 27 but mounted to turn loosely upon said shaft 15. Said sun gear 32 carries, rigidly connected therewith, the gear 33 which is in mesh with the idler gear 34, shown in dotted lines in Fig. VI, which is in mesh with the gear 35, which is rigidly mounted on said

shaft 16 upon which the suspension chain gear 13 is rigidly mounted.

The arrangement last above described is such that said shaft 15 may be turned in either direction by the wheel 25, to turn the suspension chain wheel 12 in the same direction, but contemporaneously turn the suspension chain wheel 13 in the opposite direction and thus effect relative vertical movement of the two chains 2 and 3 to tilt the trays 1 in either direction. Although it is desirable to thus tilt the trays to the extent of forty-five degrees to the horizontal, as indicated by the dotted lines in Fig. II; I provide said shaft 15 with stop means to limit its turning movement, to such an extent as to prevent overturning the trays. As indicated in Fig. VI and the right hand portion of Fig. VII; such stop means include the radially projecting arm 36 which is carried by the collar 37 in rigid relation with said shaft 15 and is adapted to encounter the stop member 38 which is a stud rigidly connected with and extending from said casing 30 parallel with said shaft 15.

During the relative vertical movements of said chains 2 and 3, effected by thus turning said shaft 15 less than one revolution; said casing 30 and the stud 38 projecting therefrom are held stationary by the worm 40, shown in Fig. VI, which is mounted to rotate in the journal bearings 41 and 42 on said frame 19; being rigidly connected with its shaft 43, conveniently by the pin 44. Said shaft 43 is squared, as indicated at 45, to afford a hold for a wrench by which it may be turned. Said worm 40 is in mesh with the worm gear 47 which is rigidly connected with said casing 30; so that the latter is normally prevented from turning when said worm 40 is stationary, but may be turned by rotation of said worm shaft 43.

Said casing 30 carries the belt wheel 50, which is rigidly connected therewith in coaxial relation with the shaft 15, but, of course, in relative rotatable relation with the latter, and said wheel 50 is connected, by the belt 51, with the belt wheel 52, of the same diameter, which is rigidly mounted on the shaft 17; so that the latter, and the chain 4, are held stationary when said casing is held stationary as aforesaid. Said belt 51 is conveniently a chain but is referred to as a belt in the claims to avoid confusion with the tray suspension chains 2, 3 and 4. However, it is to be understood that the latter may be flexible connectors of any suitable form.

When it is desired to bodily lower the entire series of trays 1, as is done, step by step, at suitable intervals throughout the period of twenty-one days of gestation of the eggs, to progress each tray from the top to the bottom of said series, to present the eggs in the lower part of the series when they are ready

to hatch, said worm shaft 43 may be turned in the direction of the arrow marked thereon in Fig. VI to thus turn the worm gear 47 in the direction of the arrow marked thereon in said figure, and thus simultaneously lower all of said chains 2, 3 and 4, to the same extent, without disturbing the inclination of the trays, which may then happen to be inclined in either of the two positions indicated by the dotted lines in Fig. II, or otherwise. Said stop members 36 and 38 are always cooperative to limit the tilting movements of the trays, as aforesaid, regardless of the position of rotation of the casing 30 which carries said stop member 38. Moreover, by relative turning movements of the shaft 15 and the casing 30, by simultaneous movements thereof, tilting movements of the trays, in either direction, may be effected simultaneously with their downward progressive movement aforesaid.

Although the mechanism above described may be operated intermittently, manually or otherwise, as above described, said worm shaft 43 may be continuously slowly turned, by any suitable mechanism, for instance, such as described in my copending application Serial No. 203,459 filed July 5, 1927 for Letters Patent of the United States, No. 1,722,214, including an electric motor with a suitable escapement whereby the downward progression of the trays may be suitably timed. In such an embodiment of my invention, as the progressive movement of the trays is continuous, the tilting movements of the trays, which are preferably effected at intervals not exceeding six hours, are, perforce, effected contemporaneously with such progressive movement.

In order to facilitate the engagement of the pivot means 7 on the trays 1 in proper relation with the links of the chain 4; I find it convenient to support the reach of said chain which is to be thus engaged, by means of a vertically extending backing bar 53 which may be rigidly supported, in stationary position, by any suitable means, for instance, by brackets connecting it with the adjacent wall of the incubator inclosure. Said inclosure may be in the form of a room including walls with suitable bearing supports for the shafts 15, 16, and 17. However, the mechanism above described may be supported in any convenient manner, by any suitable means.

It is to be particularly noted that the location of the flexible connectors by which the trays are supported at their front ends at the extreme opposite edges of those ends facilitates the introduction of the trays between those connectors and into detachable engagement therewith; regardless of the specific construction or arrangement of the means whereby those connectors are, or may be, operated to effect tilting and lowering

movements of the trays. Moreover, such location of the tray supports permits them to temporarily detachably engage and support a tray loading device upon which the trays 5 may be slid to and from engagement with said flexible supports; which loading device is the subject matter of my copending application (141-27) Serial No. 264,321, filed March 24, 1928, for Letters Patent of the 10 United States.

Therefore, I do not desire to limit myself to the precise details of construction, arrangement or operation herein set forth, as it is obvious that various modifications 15 may be made therein, without departing from the essential features of my invention, as defined in the appended claims.

I claim:

1. In an incubator egg tray supporting 20 mechanism, the combination with only three chains, arranged to detachably support a tray between them; of means arranged to move said chains together, to lower said tray; and said means including a shaft arranged to relatively move one of said chains to tilt said tray; whereby tilting and lowering movements of said tray may be effected in coordinate relation.

2. In an incubator egg tray supporting 25 mechanism, the combination with only three chains, arranged to support a tray between them, with two of said chains at one end and one of said chains at the other end; of means arranged to move said three chains together, to lower said tray; and said means including a shaft arranged to relatively move one of said chains to tilt said tray; whereby tilting and lowering movements of said tray may be effected in coordinate relation.

3. In an incubator egg tray supporting 30 mechanism, the combination with three chains, arranged to support a tray between them with two chains at one end and one chain at the other end; of means arranged to move said three chains together, to lower said tray; and means arranged to relatively move one of said chains to tilt said tray; including three shafts having respective chain 35 wheels rigidly connected therewith and respectively supporting said chains; and means coordinately connecting said shafts, arranged to turn said shafts simultaneously and permit the turning of one shaft relatively to the other two shafts; whereby tilting and lowering movements of said tray may be effected in coordinate relation.

4. In an incubator egg tray supporting 40 mechanism, the combination with three chains, arranged to support a tray between them with two chains at one end and one chain at the other end; of means arranged to move said three chains together, to lower said tray; and means arranged to relatively move one of said chains to tilt said tray; including three shafts having respective 45

chain wheels rigidly connected therewith and respectively supporting said chains; and means coordinately connecting said shafts, arranged to turn said shafts simultaneously and permit the turning of one shaft relatively to the other two shafts; said connecting means including a differential gearing train; whereby tilting and lowering movements of said tray may be effected in coordinate relation.

5. In an incubator egg tray supporting 50 mechanism, the combination with three chains, arranged to support a tray between them with two chains at one end and one chain at the other end; of means arranged to move said three chains together, to lower said tray; and means arranged to relatively move one of said chains to tilt said tray; including three shafts having respective chain 55 wheels rigidly connected therewith and respectively supporting said chains; and means coordinately connecting said shafts, arranged to turn said shafts simultaneously and permit the turning of one shaft relatively to the other two shafts; said connecting means including a planetary gearing train; whereby tilting and lowering movements of said tray may be effected in coordinate relation.

6. In an incubator egg tray supporting 60 mechanism, the combination with supporting means including two chains, arranged to support a tray between them, at one edge of said tray; of means arranged to relatively move said chains to tilt said tray, and means arranged to move said chains together to lower said tray; whereby tilting and lowering movements of said tray may be effected independently, at different times, and contemporaneously, at the will of the operator; including two shafts; chain wheels respectively rigidly mounted upon said shafts and respectively supporting said chains; a train of gearing cooperatively connecting said shafts, including a sun gear rigidly connected with one of said shafts, a planetary gear in mesh with said sun gear and adapted to move in an orbit concentric with that shaft; a casing in which said planetary gear is journaled; means arranged to normally hold said casing from turning and movable to turn said casing; a second sun gear in coaxial relation with said first sun gear and in mesh with said planetary gear, but free to rotate independently of said first shaft; a driving gear coupled with said second sun gear; a driven gear rigidly connected with said second shaft; an intermediate gear in mesh with said driving gear and driven gear; a stop projection on said casing; and a stop member rigidly connected with said first shaft and arranged to encounter said stop projection and limit the relative rotary movement of said first shaft in said casing; whereby rotary movement of said first shaft, rigidly connected with said sun gear, effects rotary movement of said

- second shaft, in the opposite direction, to effect tilting movement of said tray; said stop mechanism limiting the inclination of said tray while said casing remains stationary; and rotary movement of said casing effects simultaneous rotation of both chain wheels in the same direction.
7. In an incubator egg tray supporting mechanism, the combination with supporting means including two chains, arranged to support a tray between them, at one end of said tray; of means arranged to relatively move said chains to tilt said tray; and means arranged to move said chains together to lower said tray; whereby tilting and lowering movements of said tray may be effected independently, at respectively different times, and contemporaneously, at the will of the operator; including two, parallel, shafts; chain wheels respectively rigidly mounted upon said shafts and respectively supporting said chains; a train of gearing cooperatively connecting said shafts, including a sun gear rigidly connected with one of said shafts, a planetary gear in mesh with said sun gear and adapted to move in an orbit concentric with that shaft; a casing in which said planetary gear is journaled; a worm gear rigidly connected with said casing; and a worm engaging said worm gear; whereby said casing may be held stationary and turned; a second sun gear, in coaxial relation with said first sun gear and in mesh with said planetary gear, but free to rotate independently of said first shaft; a driving gear coupled with said second sun gear; a driven gear rigidly connected with said second shaft; an intermediate gear in mesh with said driving gear and driven gear; a stop projection on said casing; and a radial arm rigidly connected with said first shaft, arranged to encounter said stop projection and limit the relative rotary movement of said first shaft in said casing; whereby rotary movement of said first shaft, rigidly connected with said sun gear, effects rotary movement of said second shaft, in the opposite direction, to effect tilting movement of said tray; said stop mechanism limiting the inclination of said tray in both directions, while said casing remains stationary; and rotary movement of said casing, effected by rotary movement of said worm, effects simultaneous rotation of both chain wheels in the same direction.
- 55 8. In an incubator egg tray supporting mechanism, the combination with three vertically pendent chains, arranged to support a tray between them; of means arranged to relatively move one of said chains to tilt said tray and means arranged to move said chains together to lower said tray; whereby tilting and lowering movements of said tray may be effected independently, at different times, and contemporaneously, at the will of the operator; including three shafts; chain wheels re-
- spectively rigidly mounted upon said shafts and respectively supporting said chains; a train of gearing cooperatively connecting two of said shafts and including a rotatable gear casing in coaxial relation with one of said shafts; means arranged to normally hold said casing from turning, and movable to turn said casing; a stop projection on said casing; a stop member rigidly connected with said first shaft and arranged to encounter said stop projection and limit the relative rotary movement of said coaxial shaft in said casing to less than one revolution; and means cooperatively connecting said casing and third shaft to turn together; whereby rotary movement of said coaxial shaft, effects rotary movement of the second shaft in the opposite direction to effect tilting movement of said tray; said stop mechanism limiting the inclination of said tray while said casing remains stationary, and rotary movement of said casing effects simultaneous rotation of all three shafts and chain wheels in the same direction.
9. In an incubator egg tray supporting mechanism, the combination with two chains, arranged to support a tray between them at one end of said tray; of means arranged to relatively move said chains to tilt said tray and means arranged to move said chains together to lower said tray; whereby tilting and lowering movements of said tray may be effected independently, at respectively different times, and contemporaneously, at the will of the operator; including two shafts; chain wheels respectively rigidly mounted upon said shafts and respectively supporting said chains; a train of gearing cooperatively connecting said shafts, including a sun gear rigidly connected with one of said shafts, a planetary gear in mesh with said sun gear and adapted to move in an orbit concentric with that shaft, a casing in which said planetary gear is journaled; a worm gear rigidly connected with said casing; and a worm engaging said worm gear; whereby said casing may be held stationary and turned; a second sun gear, in coaxial relation with said first sun gear and in mesh with said planetary gear, but free to rotate independently of said first shaft; a driving gear rigidly coupled with said second sun gear; a driven gear rigidly connected with said second shaft and operatively connected with said driving gear; a stop projection on said casing; a stop arm rigidly connected with said first shaft and arranged to encounter said stop projection and limit the relative rotary movement of said first shaft in said casing to less than one revolution; a third chain arranged to support said tray at the opposite end thereof; a third chain wheel supporting said third chain; a third shaft, parallel with said other shafts and supporting said third wheel; a belt wheel on said third shaft; a belt wheel

on said casing; and a belt cooperatively connecting said belt wheels; whereby rotary movement of said first shaft, rigidly connected with said sun gear, effects rotary movement of said second shaft, in the opposite direction, to effect tilting movement of said tray; said stop mechanism limiting the inclination of said tray, in either direction, to approximately forty-five degrees from the horizontal plane, while said casing remains stationary; and rotary movement of said casing, effected by rotary movement of said worm, effects simultaneous rotation of said three chain wheels in the same direction.

10. An incubator egg tray, comprising a rectangular frame, having means affording three points of suspension, in triangular relation with the center of gravity of the tray, within the triangle formed by connecting said points of suspension; whereby said tray may be supported in stable equilibrium; and wherein the points of suspension are respectively local to pivot members which are metal hooks fixed on the frame and all pointing in the same direction; whereby they may be inserted and withdrawn with respect to respective suspension chains, by respective movements in the same direction.

11. In incubator egg tray supporting means, the combination with two vertically pendent flexible connectors arranged to detachably support the front end of a tray at the opposite edges thereof; of a flexible connector arranged to detachably support the rear end of a tray; and a tray having means at the opposite edges of its front end arranged to detachably engage the connectors thereat; and having means at its rear end arranged to detachably engage the connector thereat; whereby the introduction of such trays between and into engagement with such connectors is facilitated.

12. Incubator egg tray supporting means as in claim 11; wherein the space between the connectors adapted to support the front end of the tray is at least as wide as the tray.

13. Incubator egg tray supporting means as in claim 11; wherein the means on the tray for engaging the flexible supports at the front end thereof, project laterally beyond the edges of the tray.

14. In an incubator egg tray supporting mechanism, the combination with only three flexible connectors, arranged to detachably support trays between them; of means arranged to move said connectors together, to lower said trays; and arranged to relatively move two of said connectors to tilt said trays; whereby tilting and lowering movements may be effected independently, at different times, and contemporaneously, at the will of the operator.

15. Incubator egg tray supporting mechanism as in claim 14; including three shafts having wheels, rigidly connected therewith,

and supporting said connectors; and means coordinately connecting said shafts.

16. Incubator egg tray supporting mechanism as in claim 14; including three shafts having respective wheels, rigidly connected therewith, and supporting said connectors; and means coordinately connecting said shafts, including a differential gearing train.

In testimony whereof, I have hereunto signed my name at Philadelphia, Pennsylvania, this twenty-second day of December, 1927.

WILLIAM FINNEY HILLPOT.
